PISTON SKIRT DRILLING JIG

Harold P. Phillips, Hastings, Mich., assignor to
Hastings Manufacturing Company, Hastings,
Mich., a corporation of Michigan

Application October 23, 1939, Serial No. 300,750

11 Claims. (Cl. 77—62)

This invention relates to improvements in piston-skirt drilling jigs.

The main objects of my invention are:

First, to provide a novel jig for locating and positioning a drilling tool to holes in a piston skirt adapted to receive a piston skirt expander.

Second, to provide a device of the type described which is extremely simple and inexpensive in its parts and capable of ready and quick positioning on a piston skirt.

Third, to provide a device of the type described which in operative erected position accurately locates a drill for forming an opening in a tubular cylindrical member diametrically opposite a previously formed opening.

Fourth, to provide a jig of the type described for positioning a drilling tool to form a hole at 180 degrees from a previously formed hole in a cylindrical tubular part, the said jig being of such a nature that it does not interfere with subsequent actual drilling of the member.

Fifth, to provide a jig of the type described which is compact and self-contained in nature with no likelihood of inadvertent loss of parts.

Sixth, to provide a jig of the type described which will accommodate pistons of a large range of sizes.

Further objects relating to details and economies of my invention will definitely appear from the description to follow. The invention is defined in the claims.

A structure embodying the features of my invention is illustrated in the accompanying drawing, wherein:

Fig. 1 is a plan view of a piston with the jig of my invention operatively secured thereto, the piston being partially broken away and in section to illustrate the coacting relation of the jig therewith.

Fig. 2 is a fragmentary view in section on line 2—2 of Fig. 1 illustrating further details of construction of the jig and the manner in which it coacts with the piston skirt.

Fig. 3 is a fragmentary view in side elevation further illustrating the construction and operation of the device.

Fig. 4 is a fragmentary view in section on line 4—4 of Fig. 2.

The present invention relates to a jig for enabling an opening or hole to be drilled in a piston skirt 180 degrees or diametrically opposite a previously formed opening. These openings are utilized for mounting a piston expander of the type illustrated and described in my copending application Serial No. 237,686, filed October 29,

1938, and it is of substantial importance that the holes receiving the same be disposed at exactly 180 degrees from one another. Briefly stated, the present jig is of such construction as to enable its ready and accurate positioning on a piston skirt to accomplish this purpose, and, moreover, it is simple and inexpensive in its parts and does not interfere with the drilling operation after it has been positioned.

In the drawing the reference numeral 1 indicates an internal combustion engine piston in the skirt 2 of which it is desired to provide a pair of diametrically opposed holes in spaced relation to the skirt edge and at 90 degrees from the wrist pin bosses 3.

The jig in a preferred construction consists of an angled body member 4 having a jaw member 5 depending therefrom which is of curved outline on its inner face 6 as illustrated in Fig. 4, being engageable at this point with the exterior of the skirt 2. At right angles to the depending jaw member 5 the member 4 has a rest and support 61 terminating in a pair of legs 7 forming a fork within which is pivoted an interior clamping or jaw member 8 terminating in its lower end in a jaw 9 engageable with the interior of the piston skirt. The clamping member 8 extends outwardly above the body member 4 and has an offset arm 10 in which is threaded a screw 11 coacting with the top side of the body member 4, with the result that when the screw is turned in clockwise direction the jaw members 5, 9 are urged into clamping relation to the piston skirt to secure the jig on the latter.

The arms 7 extend forwardly to a point approximately centrally of the skirt and are provided at this point with a pin 12 extending therebetween, which pin guidingly receives a locating finger 13. Finger 13 is in the form of a sheet metal stamping of U-shaped section, although it will be apparent that it might be formed from a solid piece, and has an elongated slot 14 extending parallel therewith to receive the pin 12 and permit longitudinal and pivotal movement of the finger 13 with reference to the arms 7 and the body member 4. Care should be taken that there is no lateral play of the finger in the form, as this would detract from the accuracy of the jig. Finger 13 is obviously movable and swingable in a plane which includes the axis of the skirt when the jig is properly positioned and clamped, i. e. it is in diametrical alignment with said axis and with the clamping point of members 5, 9. The finger 13 terminates in a point 15 engageable in

a hole 16 which has been previously drilled in the piston skirt.

In utilizing the jig of my invention, it is first located and clamped on the piston skirt at a point approximately 90 degrees from the wrist pin bosses by actuation of screw 11 in the manner described. Care should at all times be taken in clamping the jig that the laterally projecting rest portion 61 of the jig rests on the skirt extremity so that the holes will be uniformly positioned axially with reference to the skirt extremity. With the jig so positioned the hole 16 is formed in the skirt by the drill 17 guided by the guide hole 18 in the depending jaw member 5. The jig is then removed and loosely placed on the opposite side of the skirt with the pointer 15 extended diametrically and inserted in the just formed hole 16 in the manner illustrated in Figs. 2 and 3. This positions the jaw members 5, 9 accurately on the skirt at a point diametrically opposite the hole and, taking care that the jig rests firmly on the skirt extremity, the screw 11 is again actuated to clamp the jig in place, after which the second hole is drilled in an obvious manner.

Once the jig has been set for drilling of the second hole the finger 13 may be withdrawn rearwardly, thus clearing the exterior surface of the skirt of any objects which would interfere with its being laid flat on the table of a drill press. Accordingly, the drilling of the second hole is not interfered with by reason of the piston being at an angle to the supporting table, as is the result in many cases in which the jig employs clamps over both sides of the skirt.

It will be observed that the mounting for the positioning or locating finger 13 within the slot of the jaw member is in effect a floating mounting—that is, it may be freely adjusted within the slot, the walls of the slot however holding it against lateral movement. This also enables the jig to be used in the drilling of work of considerable range of diameters.

The above described jig is simple in its construction and self-contained so that there is no possibility of loss of parts. It is extremely accurate in its operation and is quickly and easily put in place on the piston operated on by an unskilled worker.

I have illustrated and described my improvements in an embodiment which is very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent, is:

1. A jig for drilling diametrically opposed holes in piston skirts or similar cylindrical objects, comprising a body member adapted to be positioned on the skirt in abutting engagement with the extremity thereof and extending interiorly adjacent the side thereof, a clamping member pivotally mounted on said body member and engageable with the skirt interiorly thereof to clamp the same between said members, an element engageable with said clamping member and body member to actuate the same to effect clamping engagement of the jig with the skirt, and a locating pointer mounted on said body member for angular and longitudinal movement relative thereto in a plane including the axis of the skirt, said pointer being in alinement with said jaw member whereby to extend diametrically with refer-

ence thereto when the jig is clamped on the skirt and having an extremity engageable in a previously formed hole in the skirt to locate the jig for clamping with reference to said hole, said body member having a guide hole therein in diametrical alinement with said pointer and jaw for reception of a drilling tool, said pointer being diametrically retractable from said hole when the jig has been properly clamped with reference to the latter. 10

2. A jig for drilling diametrically opposed holes in piston skirts or similar cylindrical objects comprising a body member adapted to be positioned on the skirt and having a portion extending exteriorly adjacent the side thereof, a clamping member pivotally mounted on said body member and engageable with the skirt interiorly thereof to clamp the same between said members, an element engageable with said clamping member and body member to actuate the same to effect clamping engagement of the jig with the skirt, and a locating pointer pivoted on said body member for angular movement relative thereto in a plane including the axis of the skirt, said pointer being in alinement with said jaw member whereby to extend diametrically with reference thereto when the jig is clamped on the skirt and being engageable in a previously formed hole in the skirt to locate the jig for clamping with reference to said hole, said body member having a guide hole therein in diametrical alinement with said pointer and jaw for reception of a drilling tool. 20

3. A jig for drilling a hole in a cylindrical structure in predetermined relation to a previously formed hole therein, comprising a base member engageable with said structure and having a jaw extending substantially parallel to said structure exteriorly thereof, a jaw carrying member pivoted on said body member and extending interiorly of said structure, means threaded in one of said members and engageable with the other to actuate the jaws into clamping relation to the structure, a pointer pivotally and retractably mounted on said base member, said base member having a jig opening, said pointer having a terminal portion engageable in a previously formed hole in the structure to thereby position said jaws whereby when the latter are clamped on the structure said jig opening is disposed in predetermined relation to said previously formed opening, said pointer being retractable from said previously drilled hole while said jaws are in operative clamping position. 30

4. A jig for drilling diametrically opposed holes in piston skirts or similar cylindrical objects, comprising a body member adapted to be positioned on the skirt and extending exteriorly adjacent the side thereof, a clamping member associated with said body member and engageable with the skirt interiorly thereof to clamp the same between said members, means to actuate said members to effect clamping engagement of the jig with the skirt, and a locating pointer adjustable on said body member for movement relative thereto in a plane including the axis of the skirt, said pointer being in alinement with said jaw member whereby to extend diametrically with reference thereto when the jig is clamped on the skirt and having a pointed extremity engageable in a previously formed hole in the skirt to locate the jig with reference to said hole, said body member having a drill guide hole therein in diametrical alinement with said pointer and jaw for reception of a drilling tool. 40

5. A jig for drilling diametrically opposed holes in tubular parts comprising a longitudinally slotted jaw member having a fixed jaw, said fixed jaw having a pilot opening therein, a movable jaw pivotally mounted in said slot, a clamping screw arranged through said movable jaw to engage said fixed jaw member, and a locating finger pivotally and slidably mounted in said slot and having a tapered tip engageable with a previously formed hole in the work.
6. A jig for drilling diametrically opposed holes in tubular parts comprising a longitudinally slotted jaw member having a fixed jaw, said fixed jaw having a pilot opening therein, a movable jaw pivotally mounted in said slot, a screw adjusting means for said movable jaw, and a locating finger slidably adjustable in said slot for engagement with a positioning part of the work.
7. In a device of the class described, the combination with a jaw member provided with an external fixed jaw having a pilot opening therein, a coacting adjustably mounted internal jaw, screw means for adjusting said internal jaw, and a locating finger pivotally and slidably adjustable on said jaw member and adapted for positioning engagement with a hole in the work.
8. In a device of the class described, the combination with a jaw member provided with an external fixed jaw having a pilot opening therein, a coacting adjustable internal jaw, means for ad-

justing said internal jaw, and a locating finger floatingly mounted on said jaw member and adapted for positioning engagement with a hole in the work.

9. A jig for drilling diametrical holes in tubular parts comprising a longitudinally slotted jaw member having an external fixed jaw, said fixed jaw having a pilot opening therein, an adjustable internal jaw pivotally mounted in said slot, a clamping screw arranged through said movable jaw to engage said fixed jaw, and a locating finger floatingly mounted in said slot and having a tapered tip engageable with a previously formed hole in the work.

10. In a device of the class described, the combination with a jaw member provided with a fixed external jaw having a pilot opening therein, of a coacting adjustable internal jaw, and a locating finger floatingly mounted on said jaw member and adapted for positioning engagement with the work in opposed relation to the hole to be drilled.

11. A jig for drilling diametrical holes in tubular parts comprising a longitudinally slotted jaw member having an external fixed jaw having a pilot opening therein, a coacting adjustable jaw, and a locating finger floatingly mounted in said slot and engageable with a locating part of the work.
